CLAIM

The ornamental design for a display panel for a combined clock, calendar, and weather indicator, as shown and described.

DESCRIPTION

FIG. 1 is a front perspective view of a display panel for a combined clock, calendar and weather indicator showing my new design; and,

FIG. 2 is an enlarged front elevation thereof.

The broken lines in the drawings are used to show portions of a combined clock, calendar and weather indicator that do not form part of the claimed design.
